UNITED STATES PATENT OFFICE.

JAMES H. FOSTER, OF TUSCALOOSA, ALABAMA.

COMBINED DESK, CHAIR, AND RECEPTACLE.

No. 885,594.

Specification of Letters Patent. Patented April 21, 1908.

Application filed June 18, 1907. Serial No. 379,666.

To all whom it may concern:

Be it known that I, JAMES H. FOSTER, a citizen of the United States, residing at Tuscaloosa, in the county of Tuscaloosa and State of Alabama, have invented new and useful Improvements in a Combined Desk, Chair, and Receptacle, of which the following is a specification.

This invention relates to a combined desk, chair and receptacle, particularly adapted for use in school rooms; and the object thereof is to provide in a manner as hereinafter set forth a combined desk, chair and receptacle which shall be simple in construction, readily adjustable, strong, durable, efficient in use, readily set up and comparatively inexpensive to manufacture.

With the foregoing and other objects in view, the invention consists in the novel construction, combination and arrangement of parts hereinafter more specifically described and illustrated in the accompanying drawings wherein is shown the preferred embodiment of the invention; but it is to be understood that changes, variations and modifications can be resorted to which come within the scope of the claims hereunto appended.

In describing the invention in detail reference is had to the accompanying drawings wherein like characters denote corresponding parts throughout the several views, and in which—

Figure 1 is a perspective view of a combined desk, chair and receptacle in accordance with this invention; Fig. 2 is a detail of the adjustable support for the chair; Fig. 3 is a detail of the adjustable support for the desk; Fig. 4 is a detail showing the end of one of the connecting arms between the receptacle support and the vertically-adjustable support for either the chair or desk, and, Fig. 5 is a detail showing the shiftable support for the chair and desk.

Referring to the drawings by reference characters, 1 denotes a desk top, the lower face of which is secured to a bracket 2 formed of a plurality of arms 3, each of which is provided with an opening 4 to receive holdfast devices for securing the desk thereto. The arms 3 terminate at their lower ends in a sleeve 5. A like construction of bracket 2 is secured to the lower face of the chair seat 6 to which is attached a back 7. A set-screw 8 extends through the sleeve 5 for preventing

the bracket from shifting when mounted upon a support to be hereinafter referred to.

The reference character 9 denotes an upwardly-extending, inclined member having the forward face thereof toothed, as at 10 and the upper portion bent in a curvilinear manner or offset as at 11 and which terminates in a flange 12 from which extends a pintle 13. The flange 12 constitutes a support for the sleeve 5 and the pintle 13 extends up through said sleeve 5. The member 9 has the lower end thereof extending in an upwardly-inclined standard 14 substantially U-shaped in cross section and having the inner face of the front thereof toothed, as at 15, such teeth 15 adapted to engage with the teeth 10 of the member 9. The lower end of the standard 14 is formed with laterally-extending apertured lugs 16 through which extend suitable holdfast devices for securing the standard in position.

The reference character 17 denotes an upwardly-extending inclined member having the rear face thereof formed with a series of teeth, as at 18. The member 17 at its top is formed with a flange 19 from which projects a pintle 20. The flange 19 is adapted to support the sleeve 5 of the bracket 2 which is attached to the chair seat 6 and the pintle 20 extends through the sleeve 5 of such bracket. The member 17 projects at its lower end into an upwardly-extending inclined standard 21 which is substantially U-shaped in cross section and has the inner face of the rear portion thereof toothed, as at 22. The teeth 22 are adapted to engage with the teeth 18 of the member 17. The member 17 and standard 21 incline in an opposite direction with respect to the direction in which the member 9 and standard 14 extend and by such an arrangement provision is made for the horizontal adjustment of the chair with respect to the desk—that is to say, if the chair and desk are lowered they will be moved toward each other; if raised they will be moved further apart. Such arrangement provides for various sizes of pupils.

At one side of the chair and desk a receptacle for books or other objects is arranged, said receptacle being indicated by the reference character 23 and which has secured thereto a keeper 24 at one side of the center of said receptacle, said keeper 24 being pivotally mounted upon the rod 25 and by such

construction the receptacle 23 is pivoted upon the bar 25, as well as being counterbalanced so that the receptacle can be shifted to enable the pupil to readily remove the contents therefrom and when pressure is removed from the receptacle 23 it will readily assume its normal position owing to its being counter-balanced. The rod 25 has its ends secured in a pair of uprights 26 formed integral with a curvilinear connecting arm 27. The latter terminates at its rear end in a curvilinear connecting rod 28. Brace members 29 and 30 are provided for the uprights 26. Depending from the lower face of the connecting arm 27 is a hollow extension 31 which constitutes a socket for the upper end of a vertically-extending support 32, the latter at its lower end being flanged as at 33 and through which extend holdfast devices for securing the support in position. The extension 31 is vertically adjusted upon the support 32 and is retained in its adjusted position by the set screw 34.

The connecting arm 27 has projecting from its outer end a U-shaped clamp 35 which is adapted to straddle the upright 14. The clamp 35 is formed with a laterally-extending apertured lug 36 which registers with a laterally-extending lug 37 formed integral with the upright 14. Through the lugs 36, 37 the holdfast device 38 extends for connecting the clamp to the member 14. Extending through the clamp 35 is a binding screw 39 which is adapted to engage the member 9 for retaining the teeth of said member in engagement with the teeth 15, thereby fixedly securing said member 9 in its adjusted position. The outer end of the connecting arm 28 is provided with a U-shaped clamp 40 which is adapted to surround the upright 21 and said clamp 40 has projecting from one side thereof a laterally-extending apertured lug 41 which registers with a laterally-extending lug 42 formed integral with the upright 21. A holdfast device 43 extends through said lugs 41, 42 for connecting the clamp to the upright 21. Extending through the clamp 40 is a binding screw 44 which is adapted to engage the member 17 so as to retain the teeth 18 in engagement with the teeth 22 thereby fixedly securing the upright 17 in its adjusted position.

From the foregoing construction and arrangement of parts it is evident that the chair, as well as the desk, is vertically adjustable and the same is true of the receptacle 23. By arranging the receptacle 23 in the manner as stated, books or other objects are in the convenient reach of the pupil, and owing to the manner of mounting the receptacle 23, it will always assume its normal position so as not to be a source of inconvenience to the pupil.

By connecting the desk and chair through the medium of the brackets 2, respectively

to the inclined member 10 and member 17, the chair and desk can be adjusted when occasion so requires. The connecting arms 27, 28 not only act as a means for carrying the clamps which are provided with binding screws for retaining the chair and desk in the position to which they have been adjusted, but further act as a means to confine the pupil within certain limits so that one pupil cannot interfere with another. It will furthermore be evident that the arrangement of chair, desk and receptacle in a manner as hereinbefore set forth permits of entry and egress from or by only one aisle, thus conducting to good order and promoting system, rendering it less difficult to sweep the floor, being more easily and less expensive to attach to the floor, as well as more stable when fastened in position than a separate chair or desk.

What I claim is—

1. The combination of a desk, a chair, a vertically-adjustable support for the desk and for the chair, a pivoted receptacle, and vertically-adjustable means for the receptacle having connecting arms attached to the supports for the desk and chair.

2. The combination of a chair, a vertically-adjustable support therefor, a desk, a vertically-adjustable support therefor, a receptacle, a vertically-adjustable support therefor provided with a pair of connecting arms attached to the supports for the chair and desk and provided with means for securing the chair and desk in their adjusted positions, and means for pivotally connecting the receptacle to the vertically-adjustable means therefor.

3. The combination of a chair, supporting means therefor, a desk, supporting means therefor, a counter-balanced receptacle, and supporting means therefor connected with the supporting means for the desk and chair.

4. The combination of a desk, supporting means therefor, a chair, supporting means therefor, a receptacle, and supporting means therefor connected with the supporting means for the desk and chair.

5. The combination of a desk, a vertically-adjustable supporting means therefor, a chair, a vertically-adjustable supporting means therefor, a receptacle, a vertically-adjustable supporting means therefor, arms projecting from the vertically-adjustable supporting means for the receptacle, and clamps carried by said arms and connected to the vertically-adjustable supporting means for the chair and desk for retaining said means in their adjusted positions.

6. The combination of a desk, a vertically-adjustable supporting means therefor, a chair, a vertically-adjustable supporting means therefor, a pivoted receptacle, a vertically-adjustable supporting means therefor, arms projecting from the vertically-adjust-

able supporting means for the receptacle, and clamps carried by said arms and connected to the vertically-adjustable supporting means for the chair and desk for retaining said means 5 in their adjusted positions.

7. The combination of a desk, a vertically-adjustable support for the desk, a bracket shiftably mounted upon said support and connected to the desk, a chair, a vertically-adjustable support therefor, a bracket connected with the chair and shiftably mounted upon said last mentioned support, a receptacle, a vertically-adjustable support therefor, arms projecting from the vertically-adjustable support for the receptacle, and clamps carried by said arms and adapted to engage the vertically-adjustable supports for the chair and desk for retaining them in their adjusted positions.

8. The combination of a desk, a vertically-adjustable support for the desk, a bracket shiftably mounted upon said support and connected to the desk, a chair, a vertically-adjustable support therefor, a bracket connected with the chair and shiftably mounted upon said last-mentioned support, a pivoted receptacle, a vertically-adjustable support therefor, arms projecting from the vertically-adjustable support for the receptacle, and clamps carried by said arms and adapted to engage the vertically-adjustable supports for the chair and desk for retaining them in their adjusted positions.

9. The combination of a desk, a chair, connecting means between the chair and desk

positioned at one side thereof whereby entry and egress can only be had at the opposite side, and adjustable supporting means for the chair and desk whereby when said means is adjusted in one direction the desk and 40 chair will be moved toward each other and when adjusted in the opposite direction the chair and desk will be moved away from each other.

10. The combination of a desk, a chair, an 45 upwardly-extending and adjustably-inclined supporting means for the desk, an upwardly-extending adjustably-inclined supporting means for the chair, and means for connecting the supporting means for the desk 50 with the supporting means for the chair, said connecting means positioned at one side of the chair and desk and embodying a curved rod and a curved arm whereby entry and egress is permitted only from the opposite 55 side.

11. The combination of a desk, a chair, an upwardly-extending adjustably inclined supporting means for the desk, an upwardly-extending, adjustably inclined supporting 60 means for the chair, and a vertically-adjustable receptacle connected with the supporting means for the chair and desk.

In testimony whereof I have hereunto set my hand in presence of two subscribing witnesses.

JAMES H. FOSTER.
